SILICATE INSULATING MATERIAL

Harry M. Williams, Dayton, Ohio, assignor, by
mesne assignments, to General Motors Cor-
poration, a corporation of Delaware

Application March 30, 1929, Serial No. 351,364

1 Claim. (Cl. 106—19)

This invention relates to refrigerating apparatus and more particularly to a cabinet for use with mechanical refrigerating systems.

5 An object of this invention is to provide a cabinet with a new type of insulation.

Further objects and advantages of the present invention will be apparent from the following description, reference being had to the accompanying drawings, wherein a preferred form of the 10 present invention is clearly shown.

In the drawings:

Fig. 1 is a vertical transverse cross-sectional view of a cabinet embodying features of this invention;

15 Fig. 2 is a vertical cross-sectional view of the cabinet taken at right angles to Fig. 1;

Fig. 3 is a horizontal cross-sectional view of the cabinet taken along the line 3—3 of Fig. 1;

Fig. 4 is a view in perspective, with parts broken 20 away, of the insulation which may be used in the cabinet; and

Fig. 5 is an enlarged cross-section of the insulation.

A cabinet embodying features of this invention 25 may comprise in general a framework generally designated as 20, a food compartment generally designated as 21, insulation, generally designated as 22, and an outer casing generally designated as 23.

30 The framework may be of any suitable construction. In one embodiment the framework may include vertical rear corner angle irons 25 and vertical front corner angle irons 26. It also may include upper horizontal side angle irons 27, 35 upper corner front angle irons 28, upper rear corner angle irons 29. The framework may also include lower horizontal angle irons designated as 27a, 28a, and 29a which correspond respectively to the upper corner angle irons 27 to 29 inclusive.

40 Also, if desired, the framework may include intermediate side angle irons 27b, intermediate front angle irons 28b, and rear intermediate angle irons 29b corresponding to similarly numbered upper horizontal angle irons, angle iron 28b having its angle upwardly turned to receive the door jamb. All of these angle irons may be suitably joined at their intersections, for instance by spot-welding, and, if necessary, gussets 30 may be provided at some or all of the corners in order to 45 reinforce the structure. The framework may also include a relatively non-conducting door jamb 31 which, if desired, may include upper and lower horizontal members 32, vertical side members 33 and, if necessary, a center mullion 34.

50 These members may be made of wood, or other

non-conducting substance, and may have their intersections morticed in any suitable manner. The door jamb may be secured to the framework, for instance, by inserting it within the angles of some of the angle irons and by securing it in 5 place by means of screws 35 or the like.

The food compartment 21 may be of any suitable character. For instance it may be a box-like sheet metal structure having an offset 36 along the edge of the opening. The edge 37 may be secured to the door jamb 32 by any suitable means such as by nails or the like, not shown. Finishing strips 38 may be placed over the edge 37 as well as over the edge of some of the outer panels hereinafter to be more fully described. The compartment 21 may be porcelain enamel 10 finish if desired.

The insulation 22 may be of any suitable construction preferably comprising a layer 40 of a porous baked material hereinafter to be more 20 fully described. This baked material may be attached to the food compartment with lining, if so desired, and an embodiment for doing this is by placing bituminous cement 41 on the food compartment 21 or on the porous baked material, 25 or on both. While the bituminous cement is still in the molten condition, the porous baked material is applied to the lining, which is thus secured to the lining when the cement cools and hardens. If desired, an outer layer of bituminous cement 30 42 may also be applied to the porous baked material. Thus the porous baked material is completely enclosed in a substantially waterproof coating of bituminous cement. As shown, the porous baked material is in the form of slabs 35 which may be applied successively to the food compartment.

The outer casing may comprise a plurality of panels applied in any suitable manner. For instance the panel structure may be substantially 40 as disclosed in the copending application of Henry P. Braeutigam and William C. Holbrook, Serial No. 257,989, filed February 28, 1928, to which reference is made, if necessary, for a further disclosure. If desired, cushioning pads 43 45 of cardboard, wall-board or the like may be interposed between the framework and the outer panels. This is particularly desirable when the outer panels are porcelain enameled, to prevent breakage of the enamel.

50 Suitable doors 44 are hinged to the cabinet and, for instance, may be attached to the vertical corner angle irons 26 or to the door jamb member 33 by suitable hinges and screws. If a lower compartment 50 is provided for the reception of ma- 55

chinery or the like a door 51 may also be provided and may be hinged at 52. The machinery may rest on a metal panel 53 resting on the lower horizontal frame members.

5 The porous baked material 40 preferably contains silicate of sodium and some metal reenforcement. The reenforcement may be wire mesh 60 preferably applied near both edges of the blocks 61 which are in a convenient shape for 10 application to the food compartment. The sodium silicate is preferably mixed with water, preferably not over 50% of water, and is baked in suitable ovens at temperatures generally ranging between 1000° and 1100° F. The oven is preferably a hot hearth, bottom burner of gas or oil 15 suitable to maintain a temperature of 1000° F. to 1100° F. The mixture of silicate and water is placed in suitable pans and placed in the oven for the necessary length of time which causes 20 the mixture to puff and harden into a porous baked mass. It has been found that when sodium silicate has its ratio of SiO_2 to Na_2O increased, the solubility of the baked product is decreased. Thus when the ratio of SiO_2 to Na_2O is 2 to 1 25 the resulting product is more soluble than the ratio is 3.25 to 1. Also the insolubility may be further increased by adding some substance,

preferably intermixed with the sodium silicate. A substance which has been found suitable is aluminum sulphate. For instance, the addition of 7½% of aluminum sulphate increases the insolubility somewhat. Also ammonium chloride 5 (8%) further increases the insolubility. A mixture of 5 pounds of sodium silicate, 5½ oz. of zinc oxide and 1200 cc. of water has also given good results. Thus, when water-proofing substances are added, at least 90% of all constituents other than water in the insulation is sodium silicate. Thus it has been found that blocks of the porous baked material when made as insoluble as possible, when reenforced by metal and when covered with insoluble materials, such as bituminous 10 cement 42, are excellent for insulating refrigerator cabinets.

While the form of embodiment of the invention as herein disclosed, constitutes a preferred form, it is to be understood that other forms 20 might be adopted, all coming within the scope of the claim which follows.

What is claimed is as follows:

An insulating material comprising a base of 25 dehydrated soluble silicate.

HARRY M. WILLIAMS.
